(57) **CLAIM**

The ornamental design for a clip-on decorative fish hook with magnifying lens, as shown and described.

DESCRIPTION

FIG. 1 is a top perspective view of a top, front, and right side of a clip-on decorative fish hook with magnifying lens showing my new design with the magnifying lens in a stowed, non-use position and showing a decorative fish being a largemouth bass;

FIG. 2 is a top perspective view of a top, front, and right side of the clip-on decorative fish hook with magnifying lens in an alternate position with the magnifying lens in an extended, line-of-sight position and showing the decorative fish being a largemouth bass;

FIG. 3 is a top plan view thereof;

FIG. 4 is a bottom view thereof;

FIG. 5 is a right side elevation view thereof;

FIG. 6 is a left side elevation thereof;

FIG. 7 is a rear elevational view thereof;

FIG. 8 is a front elevational view thereof;

FIG. 9 is a top plan view of a second embodiment showing the decorative fish being a rainbow trout;

FIG. 10 is a top plan view of a third embodiment showing the decorative fish being a redfish;

FIG. 11 is a top plan view of a fourth embodiment showing the decorative fish being a striped bass; and,

FIG. 12 is a top plan view of a fifth embodiment showing the decorative fish being a yellow fin tuna.

The magnifying lens can be used, for example, as an aid for tying fishing knots.

The invention is illustrated in FIGS. 1-8 where the decorative fish is a largemouth bass.

FIGS. 9-12 show alternative embodiments of the invention similar to that shown in FIGS. 1-8, except the top plan view has been modified to show a different decorative fish as stated in the descriptions for FIGS. 9-12.

The broken lines in the drawings illustrate portions of the article that form no part of the claimed design.

1 Claim, 5 Drawing Sheets
